ELECTRICAL WAVE FILTER SYSTEM

John C. Wilson, Bayside, N. Y., assignor to
Hazeltine Corporation, a corporation of Dela-
ware

Application August 15, 1940, Serial No. 352,805

14 Claims. (Cl. 178—44)

This invention relates to electrical wave filter systems having approximately a predetermined amplitude-frequency characteristic and a substantially linear phase-frequency characteristic and relates particularly to such networks having an amplitude-frequency characteristic related to that of a scanning aperture or scanning spot operating at a predetermined velocity.

It is frequently desirable in wave-signal translating systems to provide a wave filter system having a predetermined amplitude-frequency characteristic over a given frequency range in order to compensate for amplitude distortion introduced in some other part of the system or to effect an amplitude distortion of the translated signal for some other purpose. It is well known that, for distortionless transmission of a wave signal, one requisite is that the over-all phase-frequency characteristic of the translating system must be linear. However, in general, it has not been possible to construct a network having certain desirable amplitude-frequency characteristics over a range of frequencies which also has a linear phase-frequency characteristic over the same range of frequencies. Accordingly, it has been the practice, in those cases where a network with such a predetermined amplitude-frequency characteristic is required, to provide a network having the desired amplitude-frequency characteristic, but which does not have a linear phase-frequency characteristic, and also to include in cascade therewith some type of phase-correcting network with a uniform amplitude-frequency characteristic; that is, the required amplitude-frequency characteristic is provided by a network which does not have a linear phase-frequency characteristic, and some other network, which has a compensating phase-frequency characteristic but which does not effect an amplitude distortion, is connected in cascade therewith.

It is, therefore, particularly desirable to provide an improved electrical wave filter system having approximately any desired predetermined amplitude-frequency characteristic and which also has a linear phase-frequency characteristic. For instance, such a network may be required to procure the same type of distortion as, or to compensate for the distortion effected by, a scanning spot or aperture in a television system. It is well known that any such scanning aperture which is symmetrical about an axis at right angles to the direction of scanning introduces an amplitude distortion into the system due to the finite width of the aperture but that such an

aperture introduces no phase distortion into the system. The amplitude distortion for any such aperture operating at a predetermined velocity can be computed in terms of an electrically equivalent amplitude-frequency characteristic and it is frequently desirable to simulate such a characteristic in an electrical system, or to provide a network which is effective to compensate therefor. Furthermore, it is well known that the scanning spot of a television system effects a distortion analogous to that of an aperture and it will be understood that in the following specification the term "aperture characteristic" is intended to include also the characteristic of a scanning spot.

The amplitude-frequency characteristic of a scanning aperture of the type under discussion comprises frequencies of zero response, the wave lengths of signals of such frequencies being integral sub-multiples of the aperture width. For a further explanation of these characteristics of a scanning aperture, see the material under the heading of "Finite aperture effects" beginning on page 84 of applicant's treatise entitled "Television Engineering" published by Sir Isaac Pitman and Sons, Ltd., London, 1937.

In the following specification and claims the present invention is described and claimed in terms of an electrical wave filter having a predetermined amplitude-frequency characteristic related to that of a scanning aperture operating at a predetermined velocity. It will be understood, however, that this treatment has been adopted to facilitate the description of the invention and that the wave filter systems of the invention are not necessarily associated with any particular scanning aperture but are of general utility as electrical wave filter systems having substantially linear phase-frequency characteristics and any desired predetermined amplitude-frequency characteristics.

It is an object of the invention, therefore, to provide an electrical wave filter system of the type under discussion which is not subject to one or more of the above disadvantages of prior art arrangements.

It is a further object of the invention to provide an electrical wave filter system having approximately a predetermined amplitude-frequency characteristic and a substantially linear phase-frequency characteristic over a given frequency range, which characteristic is substantially identical to or related to that of a scanning aperture operating at a predetermined velocity.

It is still another object of the invention to

provide an electrical wave filter system having a predetermined amplitude-frequency characteristic and a substantially linear phase-frequency characteristic over a given frequency range, which characteristics are substantially complementary over the pass band of the filter to the corresponding characteristics of a particular scanning aperture operating at a predetermined velocity.

In accordance with the invention, an electrical wave filter system having approximately a predetermined amplitude-frequency characteristic, related to that of a scanning aperture operating at a predetermined velocity, and a substantially linear phase-frequency characteristic over a given frequency range comprises, a multisection delay network effectively including a plurality of filter sections having a pass band including the given frequency range. The delay network is designed to have a time delay at least as great as, and in the preferred embodiments, a time delay which is an integral multiple of, the period corresponding to the first zero-response frequency of the aperture. The system also includes means for deriving voltages from a plurality of junctions of the filter together with means for adding the derived voltages with predetermined relative magnitudes and polarities which are effectively symmetrical about a given point of the filter to procure the desired amplitude-response characteristic.

For a better understanding of the present invention, together with other and further objects thereof, reference is had to the following description taken in connection with the accompanying drawings, and its scope will be pointed out in the appended claims.

Figs. 1 and 2 of the drawings comprise graphs utilized to explain the general theory of the electrical wave filter system of the invention; Fig. 3 is a circuit diagram of an electrical wave filter system in accordance with the invention for providing an amplitude-frequency characteristic substantially identical to that of a square scanning aperture operating at a predetermined velocity; Fig. 4 of the drawings is a circuit diagram of an electrical wave filter system in accordance with the invention which may provide any predetermined amplitude-frequency characteristic; Fig. 5 illustrates a simplified electrical wave filter system for procuring an amplitude-frequency characteristic which is compensatory to that of a square scanning aperture operating at a predetermined velocity; while Figs. 6a, 6b, 6c, and 6d comprise a series of graphs utilized to explain the operation of the circuit of Fig. 5.

Reference is made to the curves of Fig. 1 for an introduction to the theory of the present invention. Fig. 1 comprises a graph A which represents a given brightness distribution which is to be scanned with a predetermined velocity by a square aperture of size x . Any such brightness-distribution characteristic can be analyzed into its harmonic components, one of which is shown as a dotted sinusoid B of wave length kx on the displacement axis. When the wave length kx is equal to, or any integral sub-multiple of, the dimension x , corresponding components of the brightness-distribution characteristic are completely elided. This is the case for $k=1$, $k=\frac{1}{2}$, $k=\frac{1}{3}$, etc. and, due to the constant velocity of scanning, the brightness components so considered can be converted into frequencies to derive the attenuation characteristic of Fig. 2, which is plotted up to the frequency for which

$k=\frac{1}{2}$, the frequencies corresponding to $k=1$, $k=\frac{1}{2}$, etc., being termed zero-response frequencies or simply zero frequencies. The characteristic of Fig. 2 is thus a well-known type associated with a square scanning aperture operating with a predetermined velocity. For apertures which are symmetrical about any line at right angles to the direction of travel, there is no phase distortion introduced by such a scanning aperture. Consequently, a scanning aperture may be said to act as a unique kind of filter having a predetermined amplitude-frequency characteristic and having no phase distortion.

In Fig. 3, there is represented an electrical wave filter system in accordance with the present invention which has an amplitude-frequency characteristic similar to that of Fig. 2, or related to that of a scanning aperture operating at a predetermined velocity, and which has a substantially linear phase-frequency characteristic. This electrical wave filter system comprises a multisection delay network, effectively including a plurality of nondissipative confluent filter sections having series-inductance arms L and shunt-capacitance arms C. The filter section is thus of the low-pass filter type and is designed to have a pass band including all the frequencies of the range for which the electrical wave filter system of the invention is to provide a predetermined amplitude-frequency characteristic. Input terminals 10, 11 and output terminals 12, 13 are provided for the wave filter system. A terminating resistor R, which is effectively an impedance-matching element, is connected across the end of the filter remote from the input terminals 10, 11 to prevent reflections in the filter circuit. The delay network is designed to have a time delay at least as, and preferably equal to or equal to an integral multiple of, great as the period of the first zero-response frequency of the aperture the characteristic of which is to be approximated by that of the filter.

In order to derive voltages from a plurality of junctions of the filter associated with a portion of the filter having a time delay substantially equal to the period of the first zero-response frequency of the related aperture, there are provided vacuum tubes 15-19, inclusive, having input electrodes individually coupled across successive filter junctions and output electrodes coupled to a common load resistor 20 across which are connected the output terminals 12, 13 of the electrical wave filter system of the invention. Thus, tubes 15-19, inclusive, and load resistor 20 provide means for adding voltages derived from the filter with predetermined relative magnitudes and polarities which are effectively symmetrical about a given point of the filter to derive the desired amplitude-frequency characteristic. A unidirectional operating voltage is supplied for the vacuum tubes 15-19, inclusive, by means of source 21.

In considering the operation of the electrical wave filter system just described, it will be seen that, if a signal is applied to input terminals 10, 11 a distorted output signal is derived from the output terminals 12, 13. Let us suppose that the magnification factor of each of vacuum tubes 15-19, inclusive, in conjunction with the common load resistor 20 is such that, if the signal voltages at all the tapping points on the delay network, i. e., at all the tube grids, were exactly in phase, the output voltage from terminals 12, 13 would be equal in magnitude to the input voltage at

terminals 10, 11. This means that, if n is the total number of tappings of the delay network, the magnification of each tube is effectively $1/n$. Let T be the total delay of the network in seconds between the first and last tapping points. Then as n approaches an indefinitely large number, T being held constant, the distortion effected by the filter becomes indistinguishable from that effected by a rectangular scanning aperture moving at a predetermined velocity parallel to one side.

For a pure sinusoidal input of angular frequency ω , the output, in phase and magnitude relative to the voltage at the central tapping point, for an odd number of tapping points, is given by:

$$\begin{aligned} & \frac{a}{n} \sin \omega t \\ & + \frac{a}{n} \sin \omega(t-d) + \frac{a}{n} \sin \omega(t-2d) + \dots \text{etc.} \\ & + \frac{a}{n} \sin \omega(t+d) + \frac{a}{n} \sin \omega(t+2d) + \dots \text{etc.} \\ & = \frac{a}{n} \sin \omega t + 2 \frac{a}{n} \sin \omega t \\ & \quad (\cos \omega d + \cos 2\omega d + \cos 3\omega d + \text{etc.}) \end{aligned}$$

where,

a is the amplitude of the input sinusoid,
 d is the time delay in seconds between one tapping point and the next,
 ω is the angular frequency, and
 t is time in seconds.

Now, $(n-1)d=T$, so that we may write:

$$d=T/(n-1)$$

Hence, the output voltage may be written in the form:

$a \sin \omega t$

$$\left[\frac{1}{n} + \frac{2}{n} \left(\cos \theta + \cos 2\theta + \cos 3\theta + \dots \cos \frac{n-1}{2}\theta \right) \right]$$

where $\theta = \omega T/(n-1)$. This can be reduced, using a well-known relation (see "Fourier's Series and Spherical Harmonics," by W. E. Byerly, page 32, section 20) to the form:

$$\begin{aligned} & a \sin \omega t \left\{ \frac{1}{n} + \frac{2}{n} \left[-\frac{1}{2} + \frac{1}{2} \frac{\sin n\theta/2}{\sin \theta/2} \right] \right\} \\ & = a \sin \omega t \left[\frac{\sin n\omega T/2(n-1)}{n \cdot \sin \omega T/2(n-1)} \right] \quad (1) \end{aligned}$$

When n becomes large, this approaches:

$$a \sin \omega t \left[\frac{\sin \omega T/2}{\omega T/2} \right] = a \sin \omega t \left[\frac{\sin \pi f T}{\pi f T} \right] \quad (2)$$

where f represents frequency. This is obviously the same type of attenuation factor as that of a rectangular aperture for which the first zero frequency, f_z , is equal to $1/T$. On putting $f=1/T$, for example, the above Expression 2 vanishes, as it should.

Expression 1 gives the output voltage for a filter network of the kind shown in Fig. 3 for a finite number of tappings, in terms of the number n of tapping points. Although the above reasoning was carried through for a filter having a central tapping point, i. e., having an odd number of tappings, closely similar expressions can readily be derived when n is even. The final result, for a large number of tapping points, is precisely the same whether n is odd or even.

It is thus seen that in the circuit of Fig. 3, means including tubes 15-19, inclusive, are provided for deriving and adding voltages from the filter which are effectively symmetrical about the

point of the filter to which tube 17 is coupled, the derived voltages being of substantially equal magnitudes and of the same polarity and being derived from a plurality of functions of the filter which are evenly electrically displaced and symmetrically disposed about a given point of the filter.

In Fig. 4 of the drawings, there is illustrated an electrical wave filter system which may be designed to have any predetermined amplitude-frequency characteristic and may, for instance, be utilized to provide an amplitude-frequency characteristic which is complementary or compensatory to that of the filter network of Fig. 3. 15 The filter network of Fig. 4 comprises a multi-section delay network similar to that of Fig. 3 and similar circuit elements have identical reference numerals. The delay network of Fig. 4 is designed to have a time delay which is substantially equal to the period corresponding to the first zero-response frequency of a related scanning aperture. In order to obtain a predetermined amplitude-frequency characteristic from the system of Fig. 4, there is provided means for 20 deriving the fundamental component of a periodic signal-input wave having a period equal to the time delay of the network, together with means for obtaining certain of the harmonic-frequency components thereof and for combining 25 the derived components with predetermined relative magnitudes and polarities. Specifically, means are provided for obtaining the fundamental, the second, third, and fourth harmonic components of the applied signal, together with 30 means for adding the derived components with such relative magnitudes and polarities as effectively to procure the desired amplitude-frequency characteristic. Only these harmonic components are utilized in the arrangement of Fig. 4, because 35 such a system becomes quite complicated if correction is made for many harmonic components.

In order to derive the even harmonic components, the signal applied to the input terminals 10, 11 and a signal derived from the mid-junction 25 of the filter are combined, duplex combining amplifier tube 26 being provided for this purpose. Thus, the tube 26 has one control electrode coupled to terminal 10 and another control electrode coupled to the mid-junction 25 of the filter so that even harmonic components of the applied signal appear across the cathode load resistor 28 of the tube without a reversal of polarity. The even harmonic components of the applied signal are also developed by a duplex 55 combining amplifier tube 30 to which is applied a signal from a junction 29 of the filter displaced one-fourth of the length of the filter from the terminals 10, 11 and a signal from junction 32 of the filter displaced three-fourth of the length 60 of the filter from terminals 10, 11. These signals are combined in tube 30 to develop a voltage across a cathode load resistor 31 thereof which includes only the even harmonic components of the applied signal, specifically including the 65 second and fourth harmonic components of the applied signal, only signals of these frequencies being dealt with, as explained above, in the interest of simplicity.

In order to obtain the fourth harmonic component of the applied signal, the signal outputs of tubes 26 and 30 are added in a duplex combining amplifier tube 33, such fourth harmonic component being developed across a cathode load resistor 35 and an anode load resistor 37 of the tube.

In order to develop the second harmonic component of the applied signal, a duplex combining amplifier tube 36 is provided for subtracting the fourth harmonic component of the applied signal from the component of the signal including the second and fourth harmonic components. Thus, the fourth harmonic component derived from anode load resistor 37 is applied through a coupling condenser 38 and grid-leak resistor 39 to an input electrode of vacuum tube 36 and the signal developed across cathode load resistor 28 and containing only the second and fourth harmonic components of the applied signal is applied to another input electrode thereof. There is thus produced across the cathode load resistor 40 of tube 36 signals including only the second harmonic component of the applied signals.

In order to develop the third harmonic component of the signal input to the delay network, the system includes a cathode load combining amplifier 41 to which are applied voltages from junctions of the filter displaced one-third of the length of the delay network; specifically, voltages derived from terminal 10, junction 42, and junction 43 are individually applied to separate input electrodes of the combining amplifier 41 to develop in its cathode load resistor 44 the third harmonic component with the same polarity as it appears in the input signal of the system.

In order to derive the fundamental component of the translated signal, the harmonic components thereof, developed as described, are subtracted from the signal input to terminals 10, 11. An anode load combining amplifier 45 is provided for the purpose of combining the derived harmonic components of the applied signal, the derived second, third, and fourth harmonic components of the signal being individually applied to the input electrodes of the amplifier so that a voltage proportional to the harmonic content of the signal, but of opposite polarity, is developed across an anode load resistor 46 of the amplifier. The voltage developed across resistor 46 is combined in a duplex combining amplifier tube 48 with the signal input to the system derived from terminals 10, 11 to develop in the load resistor 49 thereof the fundamental component of the applied signal. The fundamental component of the applied signal together with each of the harmonic components thereof are thereafter applied to a combining device 50 having output terminals 12, 13 from which the signal output of the electrical wave filter system of the invention is derived. In considering the operation of the system of Fig. 4, it will be seen that a means has been provided for deriving the fundamental component as well as the second, third, and fourth harmonic components of the signal input to terminals 10, 11 and for combining these signals in device 50 with any desired relative magnitudes and polarities. The principle used to derive the harmonic components of the signal is analogous to that described in an article in "Practical Mathematics," entitled "Section 45. Perry's tabular method," by Nels Johann Lennes, published by the Macmillan Company in 1936. Therefore, it will be seen that any desired amplitude-frequency characteristic can be obtained from the wave filter system of Fig. 4 by combining the harmonic components of the signal input to the system with such relative magnitudes and polarity as to procure the desired effective amplitude-frequency characteristic. Specifically, the net-

work of Fig. 4 can be made to provide an amplitude-frequency characteristic which is similar to, or compensatory to that of, Fig. 2, and thus to that of a scanning aperture, simply by combining the harmonic components of the applied signal with the correct magnitudes and polarities to procure the required signal output. More particularly, the signals may be combined to produce an amplitude-frequency characteristic which is geometrically complementary to that of Fig. 2. Therefore, the network of Fig. 4 can be used in an electrical system to compensate for distortion effected by an aperture having the characteristic illustrated in Fig. 2. It will be seen that the signal translated by the delay network of Fig. 4 is the same at input terminals 10, 11 and at the resistor R. Therefore, the network of Fig. 4 is one in which voltages are derived from various filter points or junctions and comprises a means for adding the derived voltages with predetermined relative magnitudes and polarities which are effectively symmetrical about the point 25 of the filter or delay network.

However, in most practical wave filter systems, it is necessary to correct for many harmonic components of the applied signal so that, in utilizing the principles upon which the system of Fig. 4 is based, a very large number of circuit elements are required. The simplified circuit of Fig. 5 can also be proportioned to provide an amplitude-frequency characteristic which is compensatory to a given aperture characteristic. The electrical wave filter system of Fig. 5 comprises a multisection delay network effectively comprising a plurality of nondissipative filter sections or half-sections including series-inductance arms L and shunt-capacitance arms C, the delay network being terminated at its end remote from the input terminals 10, 11 by a resistor R to prevent reflection. The circuit is so designed that the network has a time delay substantially twice the period of the first zero-response frequency of the related aperture characteristic, or so that each of the two filter portions connected in cascade has a time delay substantially equal to the period corresponding to the first zero-response frequency of the related aperture. A voltage derived from the mid-junction of the filter is combined in a duplex combining amplifier tube 54 with voltages derived from the end junctions of the filter and combined in a duplex combining amplifier tube 55. The combined voltages derived from the end junctions of the filter and developed across a load resistor 59 of tube 55 are applied with a polarity opposite that of the mid-junction voltage to an input electrode of tube 54 through a coupling condenser 56, the output terminals 12, 13 being coupled across a load resistor 57 of tube 54. A tap 58 is provided on a resistor 59 in the output circuit of tube 55 and the tap is so adjusted that the amplitude of the signal output derived from resistor 59 and applied to tube 54 is substantially one-fourteenth that of the voltage derived from the mid-junction of the filter and applied to the other input electrode of the tube 54.

Reference is made to the curves of Figs. 6a-6d, 70 inclusive, for an explanation of the operation of the circuit of Fig. 5, based on its analogy to a related scanning aperture operating at a predetermined velocity.

Fig. 6a represents a brightness-versus-displacement distribution, encountered, for exam-

ple, in the spectrum of a glowing gas; that is, the curves A and B represent the brightness of a pair of spectral lines produced in the usual way by a spectrometer. Let us suppose that the distribution of light intensity along the spectrum is to be measured by means of a photoelectric cell. The cell is placed behind a "reading slit," of width indicated in Fig. 6a; and this slit is moved along the spectrum, the cell current being measured while recorded to produce the curves A' and B' of Fig. 6b. It will be seen from these latter curves that distortion has been introduced in the measurement due to the finite width of the reading slit.

Now let two auxiliary reading slits be disposed by an amount equal to one slit width be disposed so that one is on each side of the main reading slit. Additional photoelectric cells are placed behind these auxiliary slits and the currents from these additional cells, reversed in polarity as indicated by curves C', C'' and D', D'' of Fig. 6a, are added in proper magnitude to that derived from the cell behind the main reading slit. The result of this operation is indicated by curves C''' and D''' of Fig. 6a which shows an improvement both in width and steepness of the final resultant current-versus-displacement curves. That is, the curves of Fig. 6a are a better approximation to proportionality to the original brightness-distribution curves of Fig. 6a than are the curves of Fig. 6b derived from the main reading slit alone.

The legitimacy of this method of compensating for the finite width of a reading slit can be demonstrated by mathematical analysis, the details of which it is not thought necessary to include here but the results of which, insofar as they are pertinent to the present invention, may be indicated as follows:

C. Runge developed an equation which related the distortion introduced into a physical quantity by a finite width of reading slit to the magnitude of the derived or measured curve at points on each side of the point momentarily under consideration. In its original form, however, Runge's equation (see C. Runge, Zeitschr. für Math., 1897, page 206) is not adapted to the derivation of a mode of correction in a physical system. Later, this equation was transformed into a form which indicated how, in an optical system, correction terms could be applied physically to compensate for the distortion arising from the finite width of the original reading slit.

If we suppose that two additional slits are utilized spaced by one slit width on each side of the main reading slit and that I₁ and I₂ are the instantaneous currents developed by cells associated with these additional slits, the current developed by the main cell being I, we have:

$$\frac{6}{7}I_0 = I - \frac{1}{14}(I_1 + I_2) \text{ approximately}$$

where I₀ is the current which would have been

produced in a perfectly acting system without finite slit width.

A better approximation, using two more auxiliary slits and photocells disposed an equal distance beyond the first pair and giving instantaneous current I₃ and I₄, is represented by the following equation which has two additional terms:

$$\frac{30}{37}I_0 = I - \frac{23}{222}(I_1 + I_2) + \frac{1}{111}(I_3 + I_4) \text{ approximately}$$

increasingly accurate approximations being ob-

tainable if desired by adding more terms and a corresponding number of extra auxiliary slits and photocells.

Since it is only with relative intensities along the displacement axis that we are concerned in most practical cases, it is unnecessary to take account of the proportionality factor which appears as a coefficient of I₀ in the above equations, and it is only necessary for a first approximation to add to the current from the main photocell one-fourteenth of the current from two auxiliary photocells in opposite directions with

respect to the main reading slit.

A method based on the above principle for

compensating for aperture distortion by means

of auxiliary scanning apertures operating at the

same velocity as the main scanning aperture has

been described in detail in British Patent No.

279,909 to Carl Müller, and it is not believed that

any further elaboration of the basic principles

on which this type of compensating system rests

is necessary in the present specification.

The operation of the filter network of Fig. 5

best explained by analogy to aperture-correcting

systems of the above-mentioned type. Thus,

the voltage derived from the mid-junction of the

filter corresponds to the energy derived from

the main scanning aperture and the voltages de-

rived from the end junctions of the filter cor-

respond to those derived from the auxiliary scan-

ning apertures, one-fourteenth of the voltages

derived from the end junctions of the filter being

combined and subtracted from the voltage de-

rived from the mid-junction of the filter to sup-

port for the finite width of a reading slit can be dem-
onstrated by mathematical analysis, the details of

which it is not thought necessary to include here but the results of which, insofar as they are

pertinent to the present invention, may be in-
dicated as follows:

In view of the analogy presented above, if addi-

tional correction is desired, additional pairs of

filter portions can be added to the network of

Fig. 5 and that voltages of predetermined am-

plitude from each additional pair of junctions

can be alternately added to and subtracted from

the output voltage of tube 57 to provide any de-

sired precision of correction in a manner ana-

logous to that described in the above-mentioned

British patent.

It will be understood that the expression "de-

lay network effectively including a plurality of

filter sections," as used in the following claims

is intended to include a delay network including

a plurality of filter half-sections.

While there have been described what are at

present considered to be the preferred embodi-

ments of this invention, it will be obvious to those

skilled in the art that various changes and modi-

fications may be made therein without depart-

ing from the invention, and it is therefore aimed

in the appended claims to cover all such changes

and modifications as fall within the true spirit

and scope of the invention.

What is claimed is:

1. An electrical wave-filter system having approximately a predetermined amplitude-frequency characteristic, related to that of a scanning aperture operating at a predetermined velocity, and a substantially linear phase-frequency characteristic, over a given frequency range comprising a multisection delay network effectively comprising a plurality of filter sections having a pass band including said frequency range, said delay network having a time delay at least as great as the period corresponding to the first

zero-response frequency of such aperture, means for deriving voltages from a plurality of junctions of said filter, and means for adding said derived voltages with predetermined relative magnitudes and polarities which are effectively symmetrical about a given point of said filter to provide said amplitude-frequency characteristic.

2. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of nondissipative confluent filter sections having a pass band including said frequency range, said delay network having a time delay at least as great as the period corresponding to the first zero-response frequency of such aperture, means for deriving voltages from a plurality of junctions of said filter, and means for adding said derived voltages with predetermined relative magnitudes and polarities which are effectively symmetrical about a given point of said filter to provide said amplitude-frequency characteristic.

3. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections and an impedance-matching termination and having a pass band including said frequency range, said delay network having a time delay at least as great as the period corresponding to the first zero-response frequency of such aperture, means for deriving voltages from a plurality of junctions of said filter, and means for adding said derived voltages with predetermined relative magnitudes and polarities which are effectively symmetrical about a given point of said filter to provide said amplitude-frequency characteristic.

4. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of low-pass filter sections including series-inductance arms and shunt-capacitance arms and having a pass band including said frequency range, said delay network having a time delay at least as great as the period corresponding to the first zero-response frequency of such aperture, means for deriving voltages from a plurality of junctions of said filter, and means for adding said derived voltages with relative magnitudes and polarities which are effectively symmetrical about a given point of said filter to provide said amplitude-frequency characteristic.

5. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay

substantially equal to the period corresponding to the first zero-response frequency of such aperture, means for deriving voltages from a plurality of junctions of said filter, and means for adding said derived voltages with relative magnitudes and polarities which are effectively symmetrical about a given point of said filter to provide said amplitude-frequency characteristic.

6. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay which is an integral multiple of the period corresponding to the first zero-response frequency of such aperture, means for deriving voltages from a plurality of junctions of said filter, and means for adding said derived voltages with predetermined relative magnitudes and polarities which are effectively symmetrical about a given point of said filter to provide said amplitude-frequency characteristic.

7. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay at least as great as the period corresponding to the first zero-response frequency of such aperture, means for deriving voltages from a plurality of junctions of said filter, and means for adding said derived voltages with substantially equal magnitudes and the same polarity to provide said amplitude-frequency characteristic.

8. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay substantially equal to the period corresponding to the first zero-response frequency of such aperture, means for deriving voltages from a plurality of junctions of said filter which are evenly electrically spaced and symmetrically disposed about a given point of said filter, and means for adding said derived voltages with substantially equal magnitudes and the same polarity to provide said amplitude-frequency characteristic.

9. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay at least as great as the period corresponding to the first zero-response frequency of such aperture, means

for deriving voltages from a plurality of junctions of said filter, and means for adding said derived voltages with different relative magnitudes and polarities to provide said amplitude-frequency characteristics.

10. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay substantially equal to the period corresponding to the first zero-response frequency of such aperture, means for deriving voltages from a plurality of junctions of said filter, and means for adding said derived voltages with different relative magnitudes and polarities to provide said amplitude-frequency characteristic.

11. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter sections having a pass band including said frequency range, said delay network having a time delay substantially equal to the period corresponding to the first zero-response frequency of such aperture, means for deriving voltages from a plurality of junctions of said filter and for adding said derived voltages to derive the fundamental and harmonic components of a signal applied to said filter system, and means for adding said derived fundamental and harmonic components with different relative magnitudes and polarities to provide the desired amplitude-frequency characteristic.

12. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising a plurality of filter portions in cascade each having a pass band including said fre-

quency range and each having a time delay substantially equal to the period corresponding to the first zero-response frequency of such aperture, means for deriving voltages from each of the junctions of said filter network, and means for adding the voltages which are derived from alternate junctions with opposite polarity and predetermined magnitudes to provide said amplitude-frequency characteristic.

13. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising two filter portions connected in cascade and having a pass band including said frequency range, each of said portions having a time delay substantially equal to the period corresponding to the first zero-response frequency of such aperture, means for deriving voltages from each of the junctions of said filter, and means for adding the voltages derived from the end junctions of said filter to the voltage derived from the center junction thereof with opposite polarity and with predetermined relative magnitudes to provide said amplitude-frequency characteristic.

14. An electrical wave filter system having approximately a predetermined amplitude-frequency characteristic, related to that of a scanning aperture operating at a predetermined velocity, and a substantially linear phase-frequency characteristic over a given frequency range comprising, a multisection delay network effectively comprising two filter portions connected in cascade and having a pass band including said frequency range, each of said portions having a time delay substantially equal to the period corresponding to the first zero-response frequency of such aperture, means for deriving voltages from each of the junctions of said filter, and means for adding the voltages derived from the end junctions of said filter to the voltage derived from the center junction thereof with opposite polarity and with a magnitude approximately one-fourteenth that of the voltage derived from said mid-junction to provide said amplitude-frequency characteristic.

JOHN C. WILSON.
